CLAIM

I claim the ornamental design for a truck cab corner protector, as shown and described.

DESCRIPTION

FIG. 1 is a top elevational view thereof:

FIG. 2 is a bottom elevational view thereof:

FIG. 3 is a left-side perspective view thereof:

FIG. 4 is a right-side perspective view thereof:

FIG. 5 is an exploded, detailed view of the area outlined in FIG. 1:

FIG. 6 is a right-side top elevational view thereof:

FIG. 7 is a left-side top elevational view thereof:

FIG. 8 is a left-side bottom elevational view thereof:

FIG. 9 is a right-side bottom elevational view thereof; and, FIG. 10 is a top elevational view of a truck cab corner protector showing my new design thereof.

The broken lines shown (FIG. 9) of the truck cab corner protector are for illustrative purposes only and forms no part of the claimed design.
